UNITED STATES PATENT OFFICE.

CLINTON R. SIPE, OF CHICAGO, ILLINOIS, ASSIGNOR, BY MESNE ASSIGNMENTS, TO AUTOMATIC ELECTRIC INC., OF CHICAGO, ILLINOIS, A CORPORATION OF DELAWARE.

AUTOMATIC SWITCH.

Application filed September 11, 1922, Serial No. 587,502. Renewed October 30, 1926.

This invention relates in general to automatic switches for telephone systems, and may be considered as being an improvement on Patent 1,603,929, issued Oct. 19, 1926, to 5 John Wicks. The object of the invention is the provision of a new and improved rotary connector switch.

More specifically, one object of the invention is to provide a rotary connector switch 10 having both directive and automatic primary or vertical movements, and having both directive and automatic secondary or rotary movements, and having means for preventing the directive secondary movement of the switch after the switch has taken an automatic primary step.

The provision of a connector having the foregoing characteristics makes it possible to 20 form large groups of trunks by combining two or more levels, or by combining one or more levels with any desired portion of an adjacent level, while at the same time another level may be divided in several smaller groups.

25 The means by which the foregoing and other objects are accomplished will be fully set forth hereinafter, reference being had to the accompanying drawings, of which Fig. 1 is a circuit diagram of the improved connector, while Fig. 2 shows the wiring of 30 the test terminals in certain levels of the connector bank.

Referring to Fig. 1, the rotary connector is indicated by the reference character H, 35 and may be of the well-known Strowger vertical and rotary type, having circuits such that it is controlled over the two sides of the incoming trunk in series. To the right of the connector H are shown the bank terminals of a trunk line, which may extend to 40 a private branch exchange and terminate in a jack. It is understood that the trunk line shown is one of a group of trunk lines all extending to the same point.

45 In Fig. 2, the test terminals in the first five levels of the connector have been shown. The test terminals are so connected that the five levels comprise two large groups, two small groups, and three individual lines. 50 The first large group consists of three sub-groups, the first sub-group consisting of the trunk terminals in the first level, the sec-

ond sub-group consisting of the trunk terminals in the second level, and the third sub-group consisting of the first five trunk terminals in the third level. The second large group consists of two sub-groups, the first sub-group consisting of the last five trunk terminals in the third level, and the second sub-group consisting of the trunk terminals 60 in the fourth level. The first and second sub-groups in the first large group and the first sub-group in the second large group as shown, are equipped with chain relays, which are connected to the bottom test terminals of 65 their respective trunk lines. To the right of the bank terminals are shown the vertical test terminals, two for each level. When a trunk line is seized, the chain relay associated therewith energizes and completes at 70 its working contact a portion of a circuit for placing a guarding potential on one of the vertical test terminals opposite the level in which the trunk line is located. When all the trunk lines in the first and second sub-groups of the first large group are busy, 75 all of the chain relays associated therewith will be energized, and circuits will be completed through the working contacts of the chain relays for placing guarding potentials 80 on the vertical test terminals opposite such sub-groups. The first sub-group in the second large group places a guarding potential on one of its associated vertical test terminals in a similar manner. It will be noted 85 that the last sub-group in each large group and the smaller groups have no means for placing a guarding potential on their respective vertical test terminals, as none is needed. Those test contacts which are not provided 90 with chain relays are, however, connected to battery through a resistance, except in the case of straight or ordinary subscriber's lines, the test contacts of which are connected to battery through the cut off relays in the 95 usual manner. The vertical test wipers are arranged to wipe over the vertical test terminals in the vertical movement, and to disengage therefrom on the rotary movement.

On the drawing, relays which have slow 100 acting characteristics are denoted by the shading on the lower ends of their cores, or else by the solid black portion on the upper ends of their cores. The relays which have

cores shaded on the lower end are the usual so-called "slow acting" relays and are slow to fall back but not noticeably slow to pull up. On the other hand, the relays which have the upper ends of their cores shown solid black are slightly slow to pull up, in addition to being slow to fall back.

The apparatus having been described more or less in general, will now be described in connection with a detailed description of its operation. For this purpose, it will be assumed that an automatic subscriber desires to obtain connection with a subscriber in the private branch exchange served by the first large group of trunk lines. The customary subscriber's substation, individual line switch, and selector switches used by an automatic subscriber in completing a connection being well understood by those skilled in the art and forming no part of the present invention, it is believed that it will suffice to say that in response to the removal of the receiver by the calling subscriber, his individual line switch seizes an idle trunk line leading to an idle selector switch; and in response to the operation of the subscriber's calling device, the selector switch is operated to select an idle trunk line leading to another idle selector switch, or to select an idle trunk line leading to a connector switch, such as indicated by the reference character H. Let us assume that the calling subscriber has established his connection up as far as the last selector, and that the selector has come to rest on its bank contacts which are connected to the conductors 20, 21, and 22 of the connector switch H, the connector switch H being the first idle connector accessible to said selector. When the selector switch comes to rest upon the contacts associated with conductors 20, 21, and 22, the switching relay of the selector completes an energizing circuit for the line relay 4 of the connector switch as follows: from ground by way of lower winding of line relay 4, normally closed springs controlled by the armature 31, conductor 21, over the intervening switches and the subscriber's loop back to conductor 20, normally closed springs controlled by the armature 30, and through the upper winding of line relay 4 to battery. Relay 4, at armature 32 and its working contact, completes an energizing circuit for slow to release relay 5. Relay 5, upon energizing over the above traced circuit, connects ground to the release conductor 22 at armature 33 and its working contact, said ground completing a holding circuit for the switches back of the connector switch for maintaining said switches in an operated position, and, in addition, making the trunk line leading to the connector H busy to all other selectors having access thereto. At armature 34 and its working contact relay 5 prepares a circuit for the vertical magnet 15,

and at the resting contact of the same armature opens a point in the release circuit.

The calling subscriber may now manipulate his calling device in accordance with the remaining digits in the number of the private branch exchange, which in this case are 1 and 1. Due to the operation of the calling device by the calling subscriber, the circuit of the line relay 4 is interrupted in a well-known manner and the line relay, in response to this circuit interruption, deenergizes for a short interval and closes a circuit for the vertical magnet 15 as follows: from ground by the way of armature 32 and its resting contact, armature 34 and its working contact, normally closed off normal spring controlled by spring 68 and said spring, slow acting relay 6, and vertical magnet 15 to battery. The vertical magnet 15 and relay 6 energize in series, and by the operation of the vertical magnet 15, the switch shaft and wipers are raised until the wipers 75-78, inclusive, are opposite the first level and the vertical test wipers 90 and 91 are in engagement with vertical test terminals 92 and 93, respectively, which are opposite the first level. Relay 6 energizes and at armature 35 and its working contact maintains its own circuit and that of the vertical magnet 15 intact after the off normal springs have shifted, which they do on the first vertical step; at armature 36 and its resting contact opens the rotary circuit, at armature 37 and its working contact prepares a circuit for relay 9, and at armature 38 opens the vertical testing circuit.

After the first impulse, the line relay 4 again energizes and opens the circuit for relay 6 and vertical magnet 15 at armature 32. Relay 6, upon deenergizing, which it does after a short interval, switches the impulsion circuit from the vertical magnet to the rotary magnet at armature 35, and at armature 38 completes a testing circuit for vertical wiper relay 8 and vertical stepping relay 7.

If all the trunk lines in the first level are busy, there will be a ground potential on the vertical test terminal 92 caused by the energization of the chain relays shown just below the first level (Fig. 2). Each chain relay, upon energizing when its associated trunk line is seized, completes its portion of a chain of contacts by means of which ground is connected to the vertical test terminal.

Assuming that all the trunk lines in the first level are busy, the relay 6, upon deenergizing, completes an energizing circuit for the vertical wiper relay 8 as follows: from ground by the way of chain relay contacts, vertical test terminal 92, vertical wiper 90, resting contact of armature 38 and said armature, normally closed springs controlled by the armature 45, normally closed springs

controlled by armature 42, and relay 8 to battery. Relay 8, upon energizing, completes a locking circuit for itself as follows: from grounded release conductor 22, by way of armature 42 and its working contact, and relay 8 to battery. At armature 43 and its resting contact relay 8 opens the rotary impulsive circuit so that any further operation of the calling device by the calling scribe 10 is prevented from operating the rotary magnet, at armature 44 and its working contact prepares a circuit for relay 9; and at armature 45 and its working contact switches the vertical testing circuit from vertical test wiper 90 to vertical test wiper 91. Relay 7 energizes at the same time relay 8 energizes as follows: from grounded vertical test wiper 90 over a portion of the above traced circuit to armature 70 and its resting contact, and relay 7 to battery. Relay 7, upon energizing, completes a locking circuit for itself as follows: from grounded release conductor 22, working contact of armature 40 and said armature, armature 70 and its resting contact, and relay 7 to battery. At armature 39 and its working contact relay 7 completes an energizing circuit for relay 6 and vertical magnet 15 as follows: from grounded release conductor 22, working contact of armature 39 and said armature, relay 6, and vertical magnet 15 to battery. Relay 6, upon energizing, completes an energizing circuit for the rotary stepping relay 9 which energizes; and at armature 36 opens the circuit of the rotary magnet 16. The vertical magnet 15, upon energizing, raises the switch shaft and wipers opposite the next or second level and the vertical test wipers 90 and 91 come into engagement with the vertical test terminals 94 and 95, respectively. The vertical magnet 15, at its interrupter springs 70, opens the locking circuit for relay 7, whereupon said relay deenergizes and opens the circuit for relay 6 and the vertical magnet 15 at armature 39. The relay 6, due to its construction, is slow to release and maintains its armatures attracted a short interval after its circuit is broken. The vertical magnet 15, however, immediately deenergizes and completes a testing circuit for vertical stepping relay 7 by way of armatures 70 and 45 and vertical test wiper 91. The slow acting relay 6 then deenergizes, provided there is no ground potential on vertical test terminal 95. If, however, all the trunk lines in the second level are busy, there will be a ground potential on vertical test contact 95 and relay 7 will again energize as follows: from ground by the way of the contacts of the chain relays in the second level, vertical test terminal 95, vertical test wiper 91, armature 45 and its working contact, interrupter springs 70, and relay 7 to battery. Relay 7, upon energizing, again completes a locking circuit for itself at armature 40 as previously explained; and at armature 39 reestablishes the circuit for relay 6 and vertical magnet 15. The relay 6, being slow acting, has maintained its armatures attracted during the interval so that the rotary magnet 16 is not operated. The vertical magnet 15 operates again now, opens the locking circuit of relay 7, and steps the switch shaft and wipers up to the next or third level. On the deenergization of the vertical magnet, vertical test wiper 91 again tests for a ground potential, and this sequence of operations continues until the vertical test wiper 91 no longer finds a ground potential, or until it comes into engagement with a dead contact, whereupon the relay 6 deenergizes, as no circuit is established for the vertical stepping relay 7 and the vertical trunk hunting will stop. Returning now to just after the first automatic vertical step, and assuming that only the first three trunk lines in the second level are busy, the vertical stepping relay 7 will not again energize due to there being no ground potential on the vertical test terminal 95. The rotary stepping relay 9, upon energizing, as previously explained, establishes a locking circuit for itself as follows: from grounded release conductor 22 by the way of working contact of armature 46 and said armature, interrupter springs 71 of the rotary magnet 16, and relay 9 to battery. Relay 9 is maintained energized during the automatic vertical trunk hunting movement and performs no functions until the slow acting relay 6 fully deenergizes. Slow acting relay 6, upon deenergizing, opens the original energizing circuit for relay 9 at armature 37; and at armature 36 and its resting contact completes an energizing circuit for relay 13 and the rotary magnet 16 as follows: from ground by the way of grounded release conductor 22, working contact of armature 47 and said armature, armature 36 and its resting contact to junction point 99, where the circuit divides, one branch going by way of armature 66 and its resting contact, and winding of rotary magnet 16 to battery, the other branch going by way of resting contact of armature 52 and winding of relay 13 to battery. Relay 13, upon energizing, prepares at armature 58 a circuit for the rotary stepping relay 9; at armature 59 and at its working contact prepares a circuit for the testing relay 12; and at armature 60 disconnects the busy machine. The rotary magnet, upon energizing over the above traced circuit, rotates the wipers 75-78, inclusive, into engagement with the first set of bank contacts in the second level, and moves the vertical test wipers 90 and 91 out of engagement with the vertical test contacts 94 and 95, respectively. In addition, the rotary magnet opens the locking circuit

for the rotary stepping relay 9 at its interrupter springs 71, whereupon said rotary stepping relay deenergizes. Relay 9, upon deenergizing, at armature 46 opens a point 5 in its locking circuit and at armature 47 opens the circuit for relay 13 and the rotary magnet 16. The rotary magnet 16, upon deenergizing, at its interrupter springs 71 prepares a circuit for energizing relay 9. The 10 relay 13 being slow acting, maintains its armatures attracted for a short interval after its circuit is broken. As before stated, assuming the first three trunks in the second level to be busy, there will be a ground potential 15 on the test terminal which the test wiper 77 comes into engagement with, said ground extending from the connector switch occupying a multiple of that particular trunk line from a ground connection and 20 armature similar to ground and armature 64 of the connector switch H. If the first trunk line in the second level is busy, ground from the lower private bank terminal of said trunk line energizes test relay 12 by way of 25 test wiper 77, normally closed springs controlled by the armature 64, armature 59 and its working contact, armature 65 and its resting contact, winding of test relay 12 to battery. Relay 12, upon energizing, at armature 57 prepares a circuit for the transmitting 30 of a busy tone to the calling subscriber; at armature 55 and its working contact prepares a locking circuit for itself; and at armature 54 and its working contact 35 closes an energizing circuit for the rotary stepping relay 9 as follows: from ground potential on the bottom test terminal, over the short conductor connecting the upper and lower test terminals and from thence 40 by way of test wiper 76, armature 58 and its working contact, working contact of armature 54 and said armature, resting contact of armature 51 and said armature, interrupter springs 71 of the rotary magnet, and 45 winding of relay 9 to battery. Relay 9, upon energizing, completes a locking circuit for itself, and, in addition, again completes energizing circuits for relay 13 and the rotary magnet 16 as previously described. It is to 50 be noted that relay 13, being a slow to release relay, has not had time to fully deenergize before the rotary stepping relay 9 was energized, with the result that the slow to release relay is maintained energized during 55 the automatic rotary movement. The rotary magnet 16, upon energizing, steps the wipers 75-78, inclusive, into engagement with the next or second set of bank terminals in the second level, and at its interrupter springs 71 opens the locking circuit for the rotary stepping relay 9, whereupon said relay deenergizes. Relay 9, upon deenergizing, again opens a point in its own locking circuit and again opens the circuit of 60 the rotary magnet 16 and the slow to release

relay 13. The rotary magnet on deenergizing, at its interrupter springs 71 again prepares the circuit for relay 9, and the testing operation continues in the described manner until an idle set of contacts is reached.

Assuming the fourth trunk line in the second level to be the first idle trunk line, the test wipers 76 and 77 will come to rest in engagement with the test terminals 80 and 81, respectively. As the test relay 12 no 70 longer finds a ground potential on the test terminal 81 with which it is now in engagement, said relay deenergizes and prepares a circuit for the switching relay 14 at armature 55; at armature 54 opens the circuit for 75 the stepping relay 9, and at armature 57 opens the busy circuit. A short interval after relay 9 deenergizes, the slow acting relay 13 deenergizes and completes a circuit for the switching relay 14 as follows: form 80 grounded release conductor 22 by the way of armature 55 and its resting contact, lower winding of switching relay 14, resting contact of armature 59 and said armature, normally closed springs controlled by the armature 64, wiper 77, test terminal 81, conductor 73, and winding of chain relay 18 to battery. The switching relay 14 and the chain relay 18 energize in series. The chain relay 18, upon energizing, closes its 85 springs 74, thereby completing one of a chain of contacts for grounding the vertical test contact 95. The switching relay 14, upon energizing, closes at armature 62 a circuit through the low capacity condenser 98, 90 whereby the calling subscriber is given the well known ring back tone when ringing current is applied to the called line; at armature 66 permanently opens the circuit for the rotary magnet; at armature 64 grounds test 95 wiper 77; at armature 65 opens the circuit for the testing relay 12, at armature 63 completes a locking circuit for itself from grounded release conductor 22, and at armatures 61 and 67 connects ringing current to 100 the trunk line, which current operates a visual signal at the operator's position in the private branch exchange. The circuit for 105 ringing the visual signal or drop at the private branch exchange may be traced as follows: by the operation of the interrupter relay 17, grounded generator and booster battery are alternately placed on armature 72, and from thence the circuit may be traced 110 through the upper winding of the ring cut off relay 10, resting contact of armature 48 and said armature, armature 61 and its working contact, wiper 75, line bank terminal 79, through the jack, condenser and drop (not shown) at the branch exchange back 115 to line bank terminal 82, wiper 78, working contact of armature 67 and said armature, and armature 50 and its resting contact to ground. The ring cut off relay 10, due to 120 its construction, the condenser and the high 125 130

resistance of the drop in the branch exchange will not energize over the above traced circuit; the drop, however, is operated over the above traced circuit to display to the operator at the private branch exchange a visual signal by means of which the operator is informed that a connection is desired. The operator, in response to the signal, inserts the answering plug of one of her cord circuits into the jack at the branch exchange, thereby disconnecting the drop and completing a circuit for the ring cut off relay 10 by closing a relatively low resistance bridge across the trunk. Ring cut off relay 10, upon energizing, completes a locking circuit for itself at armature 49 from grounded release conductor 22; and at armatures 48 and 50 disconnects ringing current from the called line and completes the talking circuit between the calling subscriber and the operator. The back bridge relay 3 is now energized over the trunk and reverses the flow of current to the calling subscriber at armatures 30 and 31. The operator, upon ascertaining the wants of the calling subscriber, completes the desired connection and conversation is carried on in the usual manner.

After conversation is finished both parties replace their receivers. When the calling subscriber hangs up he opens the circuit of the line relay 4, whereupon said relay deenergizes and opens the circuit of relay 5. After a short interval, relay 5 deenergizes and removes ground from the release conductor 22, thereby allowing all the switches back of the connector H to release and restore to normal. In addition, at armature 33, relay 5 opens the locking circuits for relays 10 and 14, allowing said relays to release, and at armature 34 completes a circuit for the release magnet 19 to allow the switch H to return to normal. The release magnet 19 is energized over the following path: from ground at armature 32 and its resting contact, armature 34 and its resting contact, off normal spring 69 and its working contact, and release magnet 19 to battery. The release magnet is maintained energized over the above traced circuit until the shaft and wipers are returned to their normal position, whereupon the circuit of the release magnet is opened by the separation of the off normal springs.

Having described the operation of the switch in connection with establishing a connection with a private branch exchange, a brief description will now be given how the calling subscriber receives the busy signal when all the trunks to the private branch exchange are busy.

When the first digit is transmitted to the connector, the vertical magnet is operated to step the shaft and wipers up to the first level, as previously explained. With all the trunk lines busy, there will be a ground po-

tential on the vertical test contacts 92 and 95 and the vertical magnet will automatically operate as previously explained, to step the shaft and wipers up to the third level. In response to the deenergization of relay 6, 70 the rotary movement of the switch is started. The first five trunk lines in the third level being busy, the wipers are automatically rotated into engagement with the fifth set of bank contacts in the third level. As will 75 be noted in Fig. 2, the two test terminals 23 and 24 are not strapped together and the switch will stop with its wipers 76 and 77 in engagement with said test terminals, as a circuit is no longer completed for the 80 rotary stepping relay 9. Ground, however, on test terminal 24 maintains the testing relay 12 energized and said relay is locked up from the grounded release conductor 22 when relay 13 deenergizes. When relay 13 85 is fully deenergized, the busy tone is transmitted to the calling subscriber through armatures 60 and 57 in the well known manner, whereupon the calling subscriber hangs up and releases the switch as previously described. 90

It will also be noted that the last pair of test terminals in the first and second levels are not strapped although ordinarily all pairs in a group are strapped except the 95 last pair. The reason for this is that should there be but one idle trunk in one of the levels, say the second level, and two connector switches such as H should start rotating nearly simultaneously to seize said idle 100 trunk line, one of the connector switches would reach the idle trunk line before the other and make it busy to said other connector switch. The other connector switch would continue to rotate until it reached the 105 last test terminal in the second level, where it would stop and transmit to the calling subscriber a busy signal as previously described.

It will now be assumed that an automatic 110 subscriber desires to obtain connection with a subscriber in the private branch exchange served by the second large group of trunk lines and that he has established his connection up to and including the connector 115 switch H.

The calling subscriber may now manipulate his calling device in accordance with the remaining digits in the number of the branch exchange, which in this case are 3 120 and 6. In response to the operation of the calling device by the calling subscriber the shaft and wipers of the connector switch H are raised opposite the third level in the same manner as previously described. 125

Assuming that there is at least one idle trunk line in the second half of the third level, there will be no ground potential on the vertical test terminal 96 which is now engaged by the vertical test wiper 90, and the 130

relay 6, upon deenergizing as previously explained, prepares the rotary impulsing circuit without completing circuits for the vertical stepping relay 7 and the vertical wiper 5 relay 8.

The subscriber may now dial the remaining or last digit of the called number, or the digit 6. In response to the operation of the calling device by the calling subscriber, 10 the circuit of the line relay 4 is again intermittently interrupted. Each time the line relay deenergizes, it completes a circuit for the rotary magnet 16 in series with relay 11 as follows: from ground by the way of armature 32 and its resting contact, armature 34 and its working contact, normally open off-normal springs controlled by spring 68, armature 35 and its resting contact, armature 43 and its resting contact, armature 56 15 and its resting contact, winding of relay 11, armature 66 and its resting contact, and winding of rotary magnet 16 to battery. The rotary magnet 16 and relay 11 energize in series. The rotary magnet 16 steps 20 the wipers 75-78, inclusive, into engagement with the bank terminals of the sixth trunk in the third level, and moves the vertical test wipers 90 and 91 out of engagement with vertical test contacts on its first rotary 25 step. Relay 11, upon energizing, at armature 53 and its working contact maintains the impulsing circuit for the rotary magnet closed, so that said impulsing circuit will not be opened at armature 56 when the wipers are passing over busy trunks, at armature 51 and its resting contact opens the circuit to relay 9, so that said relay will not energize when wiper 76 is passing over busy trunks, and at armature 52 and its working 30 contact, completes an energizing circuit for relay 13. Relay 13, upon energizing, at armature 58 and its working contact prepares a circuit for relay 9; at armature 60 disconnects the busy machine; and at armature 59 35 and its working contact prepares the testing circuit for relay 12. The operation of the switch now depends on whether the trunk line with which the wipers are in engagement is busy or idle, and the operation in 40 either case will be the same as previously described, that is, if the sixth trunk is idle it will be connected with, whereas if this trunk is busy the switch will rotate automatically under control of relay 9 until an idle trunk 45 is found.

A brief explanation will now be given how a subscriber calls the private branch exchange served by the second large group of trunks when all the trunks in the first sub-60 group of such group are busy. In response to the operation of the calling device by the calling subscriber the connector switch H is directly operated to raise its shaft and wipers opposite the third level, and is then 65 automatically operated to raise its wipers

opposite the fourth level, after which the automatic rotary movement is initiated. The subscriber may now dial the last digit of the called number or digit 6. In response to the operation of the calling device 70 by the calling subscriber, the circuit of the line relay is again intermittently interrupted, but due to the opening of the rotary impulsing circuit by wiper relay 8 at armature 43, the operation of the line relay performs 75 no function other than to vibrate its armature in response to the interruptions in the line circuit. If the rotary impulsing circuit was not opened at armature 43 during the first automatic vertical step, the subscriber's impulses caused by the dialing of the digit 6 would be effective to rotate the wipers past the first five trunks and into engagement with the sixth set of bank contacts in the fourth level. It is, therefore, 80 plainly seen that the first five trunks in the fourth level would always be inaccessible unless some provision was made for preventing the secondary directive or rotary movement after the switch has taken an automatic vertical step. With the wipers in engagement with the first trunk line in the 85 fourth level the trunk line is tested and if found busy the switch automatically rotates the wipers in search of an idle trunk in the 90 same manner as previously described.

A brief explanation will now be given how the connector switch establishes connection with a trunk in a small group, such as the group shown in Fig. 2, comprising the 100 sixth, seventh, eighth, and ninth set of bank contacts in the fifth level. The digits necessary to call this group are the digits 5 and 6, and in response to the subscriber dialing the first digit or digit 5, the switch raises its 105 shaft and wipers opposite the fifth level.

The subscriber may now dial the remaining or last digit of the called number or the digit 6. In response to the operation of the calling device by the calling subscriber, the 110 wipers of the switch are rotated into engagement with the sixth trunk line in the fifth level. If this trunk line is busy the wipers are rotated in search of an idle line 115 and if none is found the wipers will stop on the ninth trunk line in the fifth level and transmit the busy signal to the calling subscriber in a well known manner.

The connector switch is also capable of completing connection with a private or individual line, the test terminals of three of such individual lines being shown as the fourth, fifth, and tenth sets of contacts in the fifth level in Fig. 2. Connections to these lines, however, are directly controlled throughout by the calling subscriber. The desired line is not tested until the wipers have been rotated into engagement with the bank terminals of the desired line, whereupon the desired connection is com- 120 125 130

pleted if the line is idle, or if the line is busy, the busy tone is given the calling subscriber in the well known manner.

Having fully described and ascertained the features of my invention, what is considered to be new and desired to have protected by Letters Patent will be pointed out in the appended claims.

What I claim is:

10 1. In a telephone system, a rotary connector, lines divided into groups and sub-groups accessible to said connector, means for directly controlling the operation of said connector in a primary movement to select a group, means for continuing the primary movement to automatically select a sub-group in said group, directly controlled means for operating said connector in a secondary movement, means for preventing the operation of said last mentioned directly controlled means, means for automatically starting the secondary movement, and means for automatically continuing the secondary movement to select an idle line in said sub-group.

20 2. In a telephone system, a connector switch having a directive and an automatic primary movement and a directive and an automatic secondary movement, means for directly and automatically operating said switch in its primary movement, means for preventing the directive operation of said switch in its secondary movement, and means for automatically operating said switch in its secondary movement.

30 3. In a telephone system, a rotary connector, lines divided into groups and sub-groups accessible to said connector, a primary motor magnet for operating said connector in a primary movement to select a group in accordance with a digit of the called number, means for continuing the primary movement to automatically select a sub-group in the selected group, a secondary motor magnet for operating said connector in a secondary movement in accordance with another digit of the called number, means responsive to the automatic primary movement for preventing the directive operation of said secondary motor magnet, and means for automatically operating said secondary motor magnet to select an idle line in the selected sub-group.

40 4. In a telephone system, a connector switch having a primary motor magnet directly and automatically controlled to operate said switch in a primary movement and a secondary motor magnet directly and automatically controlled to operate said switch in a secondary movement, means for directly and automatically operating said primary motor magnet to move said switch in its primary movement, means for preventing the directly controlled operation of said secondary motor magnet, and means

for automatically operating said secondary motor magnet to move said switch in its secondary movement.

5. In a telephone system, a rotary connector, lines divided into groups accessible to said connector, said groups divided into sub-groups, means for directly controlling the operation of said connector in a primary movement to select the first sub-group in the selected group, means controlled by the busy condition of the lines in said first sub-group for continuing the primary movement to automatically select another sub-group in said group, directly controlled means for operating said connector in a secondary movement, means controlled in response to said continuation of said primary movement for preventing the operation of said last mentioned directly controlled means, and means for automatically operating said connector in its secondary movement to select an idle line in said other sub-group.

6. In a telephone system, a connector switch having directive and automatic primary movements and directive and automatic secondary movements, trunk lines accessible to said switch arranged in groups and sub-groups, means for directly operating said switch to select the first sub-group in a desired group, means contingent on the busy condition of the selected sub-group for automatically operating said switch in its primary movement to select an idle sub-group, and means effective whenever said switch is operated automatically in its primary movement for preventing directive control of its secondary movement.

7. In a telephone system, a connector switch having directive and automatic primary movements and directive and automatic secondary movements, trunk lines accessible to said switch arranged in groups and sub-groups, means for directly operating said switch to select the first sub-group in a desired group, means contingent on the busy condition of the selected sub-group for automatically operating said switch in its primary movement to select an idle sub-group, means effective whenever said switch is operated automatically in its primary movement for preventing directive control of its secondary movement, and means operated automatically on the completion of the automatic primary movement for initiating the automatic secondary movement.

8. The combination, with an automatic hunting switch, of two test wipers for controlling the same hunting operation, the first of said wipers being normally connected for use, and means effective during the hunting operation for substituting the second wiper for the first.

9. The combination, with an automatic switch having automatic group and line selecting movements, of two group test wip-

- ers and two line test wipers for controlling said selecting movements, and means effective during the group selecting movement for substituting one group test wiper for the other.
10. The combination, with a three-motion automatic switch having a directive primary movement and an automatic hunting movement in the same direction, of a test wiper brought into use at the end of the directive primary movement to start the hunting movement, and a second test wiper for determining the extent of the hunting movement.
15. The combination, with an automatic directive switch, of means for giving said switch an automatic hunting movement in addition to its directive movement, a test wiper for determining whether or not said hunting movement takes place, a second test wiper for determining the extent of the hunting movement, and means responsive whenever the hunting movement is initiated for disconnecting the first of said wipers and for connecting the second.
20. The combination, with an automatic hunting switch, of two test wipers for controlling the hunting operation, the first of said wipers being normally connected to start the hunting movement, and means effective whenever the hunting movement starts for substituting the second wiper for the first.
25. The combination, with an automatic hunting switch, of two test wipers for controlling the hunting operation, the first of said wipers being normally connected to start the hunting movement, and means responsive whenever the hunting movement is initiated for substituting the second wiper for the first.
30. In a telephone system, a connector switch having directive group and line selecting movements, and means effective in case all the lines in a selected group are busy for preventing the operation of the switch in its directive secondary movement.
35. In a telephone system, a connector switch having two directive movements, groups of contacts adapted to be selected in the first of said movements, two motor magnets and circuits therefor, and means effective in case the operation of the first motor magnet positions the switch opposite a busy group for opening the circuit of the second motor magnet.
40. In a rotary connector, bank contacts arranged in levels, a group of trunk lines terminating in the contacts of a certain level and in a portion of the contacts of another level, and a second group of trunks terminating in the remaining contacts of said other level and in the contacts of a third level.
45. In a rotary connector, two groups of trunk lines, two groups of bank contacts in said connector assigned to said groups of trunk lines, respectively, and a third group of bank contacts in said connector divided between said groups of trunk lines.
50. The combination of a switch having two directive movements, of means effective under predetermined conditions for giving the switch an automatic hunting movement following the first directive movement, and means responsive to said hunting movement for preventing the second directive movement.
55. The combination, with an automatic switch having two directive movements, of groups of trunk terminals adapted to be selected by the first directive movement, and means for preventing the second directive movement in case the group selected on the first movement is busy.
60. The combination, with an automatic switch having two directive movements and two hunting movements, of groups of trunk terminals any one of which groups may be selected on the first directive movement, means dependent on the idle condition of the selected group of terminals for cancelling one hunting movement, and means operable responsive to the busy condition of the selected group of terminals for preventing the second directive movement.
65. In a telephone system, a first and a second motor magnet, means for directly generating impulses to successively operate said magnets, means for automatically generating impulses to automatically operate said magnets, and means responsive to the automatic operation of said first magnet for preventing the directly generated impulses from operating said second magnet.
70. In a telephone system, a first and a second motor magnet, means for directly generating impulses to successively operate said magnets, means for automatically generating impulses to automatically operate said magnets, and means responsive to the automatic operation of said first magnet for preventing the directly generated impulses from operating said second magnet.
75. In a telephone system, a first and a second motor magnet, means for directly generating impulses to successively operate said magnets, means for automatically generating impulses to automatically operate said magnets, and means responsive to the automatic operation of said first magnet for preventing the directly generated impulses from operating said second magnet.
80. In a telephone system, a first and a second motor magnet, means for directly generating impulses to successively operate said magnets, means for automatically generating impulses to automatically operate said magnets, and means responsive to the automatic operation of said first magnet for preventing the directly generated impulses from operating said second magnet.
85. In a telephone system, a first and a second motor magnet, means for directly generating impulses to successively operate said magnets, means for automatically generating impulses to automatically operate said magnets, and means responsive to the automatic operation of said first magnet for preventing the directly generated impulses from operating said second magnet.
90. In a telephone system, a first and a second motor magnet, means for directly generating impulses to successively operate said magnets, means for automatically generating impulses to automatically operate said magnets, and means responsive to the automatic operation of said first magnet for preventing the directly generated impulses from operating said second magnet.
95. In a telephone system, a first and a second motor magnet, means for directly generating impulses to successively operate said magnets, means for automatically generating impulses to automatically operate said magnets, and means responsive to the automatic operation of said first magnet for preventing the directly generated impulses from operating said second magnet.
100. In a telephone system, a first and a second motor magnet, means for directly generating impulses to successively operate said magnets, means for automatically generating impulses to automatically operate said magnets, and means responsive to the automatic operation of said first magnet for preventing the directly generated impulses from operating said second magnet.
105. In a telephone system, a first and a second motor magnet, means for directly generating impulses to successively operate said magnets, means for automatically generating impulses to automatically operate said magnets, and means responsive to the automatic operation of said first magnet for preventing the directly generated impulses from operating said second magnet.
110. In a telephone system, a first and a second motor magnet, means for directly generating impulses to successively operate said magnets, means for automatically generating impulses to automatically operate said magnets, and means responsive to the automatic operation of said first magnet for preventing the directly generated impulses from operating said second magnet.
115. In an automatic switch having both directive and automatic primary and secondary movements, means for automatically starting the automatic primary movement of said switch, and means effective responsive to said automatic primary movement for preventing the operation of said switch and its directive secondary movement.
120. In an automatic switch, means for directly controlling the movement of said switch in one direction, means for directly controlling the movement of said switch in another direction, means for automatically continuing the movement of the switch in the first direction, and means re-

sponsive to said last means for preventing the operation of said switch in its second directive movement.

25. In a telephone system, a group of lines terminating in a plurality of groups of line bank contacts, groups of test contacts associated with said line bank contacts, a first and a second auxiliary contact associated with each group of test contacts, means for placing a guarding potential on the first of said auxiliary contacts associated with the first group of bank contacts when all the contacts in the first group are busy, means for placing a guarding potential on the second of said auxiliary contacts associated with the second group of contacts when

all the contacts in the second group are busy, an automatic switch having access to said groups, and means controlled by the guarding potential on said first and second auxiliary contacts for causing said switch to move to a third group of bank contacts. 20

26. The combination, with an automatic switch having directive and automatic group selecting movements, of two group test 25 wipers, and means for testing with both wipers to control the automatic group selecting movement.

In witness whereof, I hereunto subscribe my name this 29th day of August, A. D., 30 1922.

CLINTON R. SIPE.
